CLAIM

The ornamental design for a gaming machine with topper, as shown and described.

DESCRIPTION

FIG. 1 is a front perspective view of a gaming machine with topper showing our new design according to a first embodiment;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a front perspective view of a gaming machine with topper showing our new design according to a second embodiment;

FIG. 9 is a front elevation view thereof;

FIG. 10 is a rear elevation view thereof;

FIG. 11 is a top plan view thereof;

FIG. 12 is a bottom plan view thereof;

FIG. 13 is a left side elevation view thereof; and,

FIG. 14 is a right side elevation view thereof.

The dashed broken lines in the figures illustrate portions of the gaming machine with topper that form no part of the claimed design.

1 Claim, 14 Drawing Sheets
